ABSTRACT OF THE DISCLOSURE

Method of continuously packaging articles in a web of heat shrinkable film wherein the web is wrapped around the articles to form an open-ended tube thereabout and the articles are arranged in spaced package groups or units within such tube including the steps of weakening the web or the tube or both at spaced zones therealong, separating the tube between spaced package groups and along a weakened zone by shrinking the tube adjacent this zone thereby to form a tube section having open end portions extending beyond the ends of a package group of articles, shrinking the open end portions of the tube section into engagement with the articles at the ends of the package group, and finally shrinking the entire tube section into engagement with all the articles in the package group thereby to form a package. Apparatus is provided for performing the above described method of packaging.

BACKGROUND OF THE INVENTION**Field of the invention**

This invention is a package-making method and apparatus and, more particularly, is directed to a novel method of and apparatus for continuously packaging a plurality of articles in heat shrinkable film to provide individual packages each consisting of a group of such articles tightly bundled together.

More specifically, the invention relates to a method of and apparatus for packaging cylindrical articles, such as cans, in heat shrinkable film to form a multipack package consisting of 6 cans (commonly referred to as a "6-pack") by separating a tube of such film wrapped around spaced groups of cans, each group consisting of 6 cans, arranged in 2 rows of 3 cans each, along a weakened zone by shrinking the tube adjacent this zone, and then by shrinking the tube section formed thereby around the 6 cans in the group in a novel manner to form a package.

Description of the prior art

Packaging arrangements and bundling and package-making apparatus of this general type are old. It is known, for example, to overwrap articles in a web of heat shrinkable film and to sever the overwrapped film between spaced groups of articles to form tube sections which are then shrunk around the group of articles in the tube section to form a package.

U.S. Pat. 3,381,443 to Copping discloses one such method of and apparatus for packaging articles wherein the articles are overwrapped in a continuous tube of heat-shrinkable film. In this patent disclosure, the articles are separated into spaced groups while within the tube which is then shrunk into engagement with the spaced overwrapped groups and the individual article packages are formed by severing the partially shrunken tube between the groups to form individual tube sections which are each shrunk around its group of articles.

In co-pending patent application Ser. No. 483,945,

2

5 filed on Aug. 31, 1965, another method is disclosed wherein spaced groups of articles are overwrapped in a continuous tube of heat-shrinkable film and packages are formed by severing the tube between the article groups to form tube sections prior to heat shrinking each section into engagement with its group of articles.

10 These methods require that the tube be completely cut, from top to bottom, between each of the spaced groups of articles while the groups are being moved through the packaging apparatus. This imposes a severe limitation on the packaging speed of the apparatus because it drastically disrupts the continuous operation of such packaging apparatus.

SUMMARY OF THE INVENTION

15 The package-making apparatus of this invention is continuous in operation.

20 Briefly described, the apparatus receives a supply of articles of substantially uniform size; forms the articles into spaced package groups; moves the spaced groups of articles continuously along a given line of movement; weakens a continuously supplied web of heat-shrinkable film at spaced zones therealong; wraps the web around 25 the spaced package groups as they move along the line of movement; seals the overlapped edges of the web together to form a unitary open-ended tube around the spaced package groups as they move along the line of movement; weakens the tube at the spaced zones therealong; separates the tube between the spaced package groups to form tube sections each having open end portions which extend beyond the ends of each package group by selectively shrinking the tube adjacent the weakened spaced zones; shrinks the open end portions 30 of each tube section into engagement with the articles at the ends of each package group of articles; and, then, further shrinks each entire tube section into close engagement with all of the articles in its package group to form packages.

35 In the multipack packaging systems for packaging beer or soft drinks, one of the major requirements is that the package making apparatus or machine be capable of operating at high speeds. In such systems, speeds up to 1200 cans per minute or above should be obtainable. This means that in packaging the classic 6-pack (i.e., 2 rows of 3 cans each) the packaging machine must turn out over 200 6-packs per minute, thus requiring a package travel speed of up to and exceeding 40 150 feet per minute through the machine.

45 Obtaining such high speeds is a difficult mechanical task. This is particularly so if any of the packaging machine operations are other than substantially continuous. For this reason, it is highly desirable to avoid any drastic intermittent motions which would greatly decrease the high speed capabilities of the machine.

50 In known packaging machines, for example, it is old to wrap a tube of film around cans in groups of 6 after which the tube is severed into tube sections each containing 6 cans while the cans and tube are under continuous movement after which the tube section is shrunk about the cans to form the 6-pack package. The severing operation is accomplished by use of a reciprocating knife which completely cuts the tube as it and the packages are moving at constant speeds. This requires that the knife be capable of both reciprocating and traveling motions because it must cut completely through the tube which means it must move the total distance of the height of such tube in a very short time. This factor alone disrupts the continuous smooth flow of the other operations of the packaging machine and to obtain even reasonably high speeds requires a complex knife mechanism.

Hence, it is seen that the speed of operation of the slowest component of the packaging machine determines the maximum speed of the total machine; and that an intermittent tube cutting or severing operation, for example, may disrupt the continuous nature of the total machine operation, at a great sacrifice to machine speed and efficiency.

Further, in the packages made by the apparatus of this invention, the cans are not only supported and contained thereby, but form an integral and necessary part of the package providing structural unity and stability to the otherwise unrelated tube or tube section. The bundled articles in the package group are a necessary component of the package so that the positioning of the articles into proper position with respect to each other and to the web wrapped around them must be carried out substantially concurrently to effect formation of the tube and formation of the package.

From this it is obvious that the speed with which this operation may be accomplished depends upon the speed and continuity of all the other and related operations of the machine including the subsequent tube separating or shrinking operations.

The present invention solves these and other problems existent in the prior art by providing a high speed package making machine of the type described that is completely continuous or substantially continuous in operation and that requires no complete severing of the tube by an intermittently operable cutting knife or other means but which efficiently and speedily separates the tube into individual tube sections in a novel and inventive manner.

In applicant's package making machine, the tube separating operation is accomplished simply by shrinking the tube along pre-weakened zones selectively formed in the film web prior to its being formed into the tube and, if desired or required, by further weakening the tube by a slight cutting action at or adjacent these weakened zones prior to the shrinking-separating operation thereby to enhance separation. In each instance, the separation of the tube occurs with little, if any, slowdown in machine speed.

It is important to note that the shrinking operation (and the components of the apparatus for performing this operation) that separates the tube into sections also shrinks the open end portions of each tube section into contact with the articles at the ends of a given package group and that both the separating and end shrinking operations occur as the tube and tube sections separated therefrom are being moved in a continuous manner through the package making machine.

Generally, in the widely used packaging technique for merchandising articles in which the articles are arranged in a sleeve or tube section severed from a tube of heat shrinkable film overwrap and the tube section is shrunk tightly around the articles, the shrinking operation is accomplished by simply passing the overwrapped articles through a conventional shrinking oven maintained at a given temperature. While this one step shrinking method appears to be convenient, it has several severe limitations.

The most prevalent of the disadvantages associated with single oven shrinking techniques centers on the restriction of using a single heat shrinking temperature. This disadvantage can be clearly appreciated when one considers the arrangement of the package and film overwrap prior to shrinking. In general, the arrangement comprises an individual package group of the articles in substantially the center of a sleeve or tube section of the film which is open at both ends. The film generally extends beyond the articles at each end, thus creating protruding areas of film. In the shrinking oven, the protruding areas are shrunk tightly around the ends of the articles while the main body of the film overwrap shrinks around the articles.

However, the amount of shrinking that the film must

undergo in various areas is not identical. In general, the protruding areas must shrink up to about 60 percent while the main body of the film shrinks only about 10 to 20 percent. Obviously, a higher temperature is required for shrinking the protruding areas than is required for the main body of the film. However, when the single oven temperature is set high enough to sufficiently shrink the protruding areas, various properties of the film, such as strength, may undergo deterioration.

Further, in applicant's package making apparatus, the tube is separated into tube sections by shrinking, followed by shrinking of such tube sections around the articles. This separation is brought about by selectively directing heat only adjacent the weakened zones of the tube as it moves continuously.

Thus, according to the present invention, there is provided a package making apparatus for directing heated air at substantially only the weakened zones of a tube to separate it into tube sections and then substantially only at the protruding areas of the tube sections whereby these areas are selectively preshrunk without adversely affecting the main body of the tube section. Furthermore, by using the present apparatus, less film overwrap is required per package since the protruding areas can be very tightly and efficiently shrunk around the package ends.

This is accomplished by providing heat shielding means for preferentially masking the top, bottom and sides of the tube next adjacent each package group (1) during the separating of the tube into tube sections, and (2) during the shrinking of the ends of the tube sections against the articles at the ends of each package group. Such heat shielding means is a part of or is operatively associated with the article and package group conveying means; thus, the continuous movement of the tube and the spaced package groups in such tube (and hence, the continuous operation of the machine) is not affected by the heat shielding operation. It is this combination which particularly adapts the apparatus of the present invention to operate at high speeds, with relative simplicity of motions, and without the use of complex additional parts.

BRIEF DESCRIPTION OF THE DRAWING

FIGS. 1 and 1a are perspective views of the package making apparatus of this invention including an article supply section, a package group forming section, a tube forming section, a film supply and web weakening section, a tube weakening section, a tube separating and package end shrinking section and a package final shrinking section;

FIGS. 2 and 2a are diagrammatic perspective views of an exemplary drive mechanism for the package making apparatus of FIGS. 1 and 1a;

FIG. 3 is a perspective view of a preferred package produced by the apparatus of the invention;

FIG. 4 is a plan view showing the tube first forming means of the tube forming section of the apparatus;

FIG. 5 is a partial side elevation of the tube first forming means of FIG. 4;

FIG. 6 is a partial end elevation of the tube first forming means of FIGS. 4 and 5;

FIG. 7 is a partial plan view showing the tube second forming means of the tube forming section of the apparatus;

FIG. 8 is a partial side elevation of the tube second forming means of FIG. 7;

FIG. 9 is an end elevation view of the tube second forming means of FIG. 7;

FIG. 10 is a partial plan view showing the tube second forming means, the tube sealing means and the tube advancing means of the tube forming section of the apparatus;

FIG. 11 is a partial side elevation of the tube second

forming means and the tube sealing means of FIG. 10; FIG. 12 is an end elevation view taken along lines 12-12 of FIG. 10;

FIG. 13 is a partial plan view showing the tube sealing means of the tube forming section of the apparatus;

FIG. 14 is an end view of the tube sealing means of FIG. 13;

FIG. 15 is a side elevation view of the tube sealing means of FIG. 13;

FIG. 16 is a side elevation view of the film supply and web weakening section of the apparatus;

FIG. 17 is an end elevation view of the film supply and web weakening section of FIG. 16;

FIG. 18 is a plan view of the film supply and web weakening section of FIGS. 16 and 17;

FIG. 19 is a side elevation of the tube weakening section of the apparatus;

FIG. 20 is a perspective view showing in greater detail the tube weakening section of FIG. 19;

FIG. 21 is a transverse cross-sectional view of the tube separating and package end shrinking section of the apparatus;

FIG. 22 is a side elevation view of the tube separating and package end shrinking section of FIG. 21;

FIG. 23 is a perspective view showing the control features of the tube separating and package end shrinking section of FIG. 21;

FIG. 24 is a perspective view of the package final shrinking section of the apparatus;

FIG. 25 is a transverse cross-sectional view of the air supply module of the package final shrinking section;

FIG. 26 is a longitudinal cross-sectional view of the air supply module of FIG. 25;

FIG. 27 is a transverse cross-sectional view of the exhaust module of the package final shrinking section;

FIG. 28 is a cross-sectional view of the web weakening means of the film supply and web weakening section of the apparatus;

FIG. 29 is a perspective view, with parts omitted for clarity, showing in sequence, the tube separating and package end shrinking operations of the apparatus; and

FIG. 30 is a partial side elevation of a modified tube weakening section of the package making apparatus of the invention.

DESCRIPTION OF THE PREFERRED EMBODIMENTS

General organization

Referring to the drawing, and FIGS. 1 and 1a in particular, it will be seen that the present invention is embodied in a method of and apparatus for packaging groups of articles in heat shrinkable film.

Such package making apparatus generally comprises an article supply section 100, a package group forming section 200, a tube forming section 300, a film supply and web weakening section 400, a tube weakening section 500, a tube separating and package end shrinking section 600 and a package final shrinking section 700.

Means for driving the various mechanical components of the apparatus are shown in FIGS. 2 and 2a and generally comprise drive sections 800 and 900.

The mechanical members or parts of the apparatus of the invention are supported by a frame 10 consisting of main frame members 11 and leg members 12 that are secured to the main frame members 11.

ARTICLE SUPPLY SECTION

Referring particularly to FIG. 1, articles 13 to be packaged by the package making apparatus of this invention are supplied from any convenient source to the article supply section 100, which includes means to feed the articles 13 in a predetermined path to the package group forming section 200. Such feed means consists of

an endless conveyor 101 having guide rails 102 and 103 suitably secured thereto for receiving the articles 13 therebetween in two contiguous rows 14 and 15 and which is adapted to move the rows of articles continuously in the direction indicated by arrow A and to the group forming section 200. The endless conveyor 101 is suitably mounted for movement on frame 10 and may be of any suitable material.

The article supply section 100 is preferably provided with a sensor means 104 for monitoring the flow of articles. The sensor means 104 is fixed secured to frame 10 in supply section 100 and is in the form of a proximity switch adapted to halt the operation of the apparatus upon detecting the absence of any flow of metallic articles in the supply section 100.

PACKAGE GROUP FORMING SECTION

The package group forming section 200 includes two article grouping screws 201 and 202 suitably mounted on the frame 10 in spaced parallel fashion to accommodate the two contiguous rows 14 and 15 of articles 13 therebetween as they are moved by the conveyor 101 through this section. Screws 201 and 202 are of substantially identical design each having a helical screw lead 203 characterized by a variable screw pitch from the inlet end 204 to the outlet end 205 thereof, except that they are oppositely threaded. The screws 201 and 202 are mounted for rotation in bearings 206 and 207, which are fixedly mounted on the frame 10 and, when rotated, each screw acts upon the row of articles immediately adjacent to it so that the rows 14 and 15 of articles are fed or moved by the conveyor 101 in timed relationship with each other. Also, the variable pitch feature of the screws 201 and 202 sequentially forms the articles 13 into predetermined spaced package groups 209 of articles, each package group preferably consisting of six articles in 2 rows of 3 articles each.

This package group forming operation is best illustrated in FIG. 1 which shows the articles 13 contacting each other upon first entering the group forming section 200 and later the articles 13 are shown in the spaced package groups 209 of six articles each that are separated from each other by spaces 210. It should be noted that the screws 201 and 202 do not directly move the articles towards the exit end 205 of the group forming section 200 but restrain the movement of the articles 13 (which movement is accomplished by the conveyor 101) and form the articles 13 into the spaced package groups 209.

The package groups 209 of articles thus formed are continuously moved from the exit end 205 of the group forming section 200 and into tube forming section 300 where a web 18 of heat shrinkable film is wrapped around the spaced groups 209 as they are continuously moved along a given line or path of movement through such tube forming section.

TUBE FORMING SECTION

The tube forming section 300 includes an endless conveyor 301, tube first and second forming means 302 and 303, tube sealing means 304, and web or tube advancing means 305, all appropriately mounted on the frame 10.

As best seen in FIGS. 1, 2, 2a, 4, 5 and 6, the conveyor 301 includes endless chains 306 and 307 having support pads 308 and rods 309 spaced therealong and connected thereto in a manner and for a purpose to be further described to provide an endless belt-type conveyor adapted to support and move the package groups 209 through the tube forming section 300.

The conveyor 301 is adapted to be driven by suitable means, such as rotatable sprocket wheels 310, that engage the endless chains 306 and 307. The sprocket wheels 310 are suitably secured to a shaft 311 that is rotatably mounted on the frame 10. The conveyor 301 is so constructed and arranged as to travel around idler sprocket

assemblies 312 and 313 each consisting of rotatably mounted shafts having sprocket wheels thereon engaging the endless chains 306 and 307 to present or define a given path of movement between the sprocket assemblies 312 and 313 that is cooperatively disposed and aligned in relation to endless conveyor 101.

The package groups 209 are transferred from the endless conveyor 101 to the endless conveyor 301 and onto the web 18 being presented to the tube first forming means 302 which is adapted to form the web 18 from a flat sheet to a sheet having a U-shaped cross-sectional configuration. The tube first forming means 302, as shown in FIGS. 4, 5 and 6, includes a tube shaper means 314 fashioned preferably of stainless steel having an oval cross-section (FIG. 6) suitably secured to a bracket 315 which is itself secured to an inverted U-shaped bracket 316 mounted on the frame members 11. The tube shaper means 314 has a substantially flat bottom 317 and curved sides 318 having a leading edge 319 providing a curved surface from top to bottom over which the web 18 is adapted to be continuously drawn or advanced for transforming the web 18 from a flat sheet to a U-shaped sheet having a substantially flat and wrinkle-free bottom.

As shown in FIGS. 4 and 5, the grouping screws 201 and 202 of the package group forming section 200 extend through the interior of the shaper 314 and are rotatably mounted at their respective ends to journals secured to the U-bracket 316. In operation, the screws 201 and 202 first move the package groups 209 into the tube shaper 314 and onto the web 18 being moved or advanced over the bottom 317 of the tube shaper 314 and onto the pads 308 of the conveyor 301. It is important to note that each individual package group 209 of articles is carried by and centered upon a single pad 308 which completely covers the bottom surface area of the group it carries.

As shown in FIG. 1, as the package groups 209 exit from the tube first forming means 302 and advance towards the tube second forming means 303, the web 18 extends over the entire bottom and up each side of the groups 209 of articles.

The tube second forming means 303, which is adapted to complete formation of the tube, includes an inverted U-shaped forming plate 318 having a flat top 319 and depending side flanges 320 and a plurality of resilient members 321 so constructed and arranged as to urge the edges of the web 18 into overlapping relationship.

The tube second forming means 303 is most clearly shown in FIGS. 7 to 11. The forming plate 318 is secured to adjustable posts 322 that are supported on cross-bars 323 by means of suitable knobs 324. The posts 322 are preferably threaded and engage the knobs 324 through a cooperatively threaded aperture extending through the latter to facilitate the vertical positioning of the forming plate 318 on the frame 10 thereby to accommodate package groups 209 of articles of different height. Cross-bars 323 are adjustably supported at each end by support posts 325 that are secured at their base 326 to the frame member 11 of the frame 10.

The resilient members 321 are preferably rubber wheels rotatably mounted at one end of a lever means 327 that is pivotably mounted at its other end to a bar shaft 328. Each bar shaft 328 is secured to a post 329 that is in turn secured to an adjustable bracket 330 that is slidably secured to a support post 325. Each bracket 330 is preferably provided with suitable means, such as a thumb screw 331, to facilitate the vertical adjustment thereof on the support posts 325 and a thumb screw 332 to facilitate the vertical positioning thereof on the posts 329. Resilient members 321 are biased against the top 319 of the forming plate 318 by resilient means, such as spring members 333, that are suitably secured to the bar shafts 328 and lever means 327 to urge the latter downwardly and transmit a downward force upon the resilient members 321. Thus, the resilient members 321 are continuously biased into

contact with the upper surface of the top 319 of the forming plate 318.

Referring especially to FIG. 7, it is seen that the resilient members 321 contact the forming plate 318 in an oblique manner, i.e., the axis of the resilient members 321 is not perpendicular to the major axis along the length direction of the forming plate 318. The disposition of the resilient members 321 at an angle with respect to the forming plate 318 causes the resilient members 321 to urge the web 18 advancing or being drawn therewith between the forming plate 318 and the resilient members 321 towards the center of the forming plate 318, and the succession of pairs of resilient members 321, such as the total of three pairs as shown in FIGS. 7 and 10, causes the edges of web 18 to overlap as shown at 334. The amount of overlap desired may be achieved by adjusting the angular position or relation of the resilient members 321 with respect to the forming plate 318 by manipulating the adjustable thumb screws 331 or 332 to achieve the desired result. As shown in FIGS. 1 and 10, as the package groups 209 exit from tube forming means 303 and advance towards the sealing means 304, the web 18 completely encloses both sides and the top and the bottom of the package groups 209, with the web edges being overlapped at the top.

The tube sealing means 304, as best seen in FIGS. 10 through 15, includes at least one sealing wheel 335 disposed on an adjustable support assembly 336 and aligned to contact the web 18 in the region of the edge overlap 334 for heating the lapped web layers and sealing them together. The support assembly 336 comprises a cradle member 337 having spaced bars 338 and a hollow cross-bar 339 secured at both ends therebetween. The bars 338 are movably secured at one end to frame member 11 and the cross-bar 339 is constructed and arranged to accommodate a screw and travelling yoke assembly consisting of a screw 340 operatively connected to an actuation means 341 and a yoke 342 which engages the screw 340 through a slot 343 in the cross-bar 339 for slidable movement therealong upon rotation of the screw 340 by turning the actuating means 341.

Referring to FIG. 13, it will be seen that the yoke 342 is adapted to accommodate a shaft 344 to which the sealing wheel 335 is connected at one end. The other end of the shaft 344 is connected to a drive wheel 345 which, in turn, is operatively connected to a shaft 346 adapted to slidably and rotatably engage a sprocket gear 347 operatively disposed for engagement with suitably driven chain means (not shown). The sealing wheel 335 is adapted to be heated for sealing the web 18 by means of power supply slip-rings 349 and 350 that are operatively connected to a conductor 351 and are adapted to contact electrically energized terminals 352 and 353, respectively, whereby the conductor 351 transmits the energy for heating the sealing wheel 335.

A slip ring 354 is also provided on the shaft 344 which is used to pick up the low voltage from a thermocouple 392 secured to the sealing wheel 335 and to pass the electric signal to a controller (not shown). The thermocouple wires are connected to the slip ring 354. The voltage is passed from the rotating slip ring 354 to the controller by means of a braided wire surface 391 which is pulled against the slip ring surface by means of tension created by springs 390. Wires, which are connected to the braided surfaces, are connected to the controller for monitoring the voltage, and the controller is calibrated in terms of temperature for adjusting the power to maintain a desired sealing temperature. Additional sealing wheels 335 may be connected in tandem by providing support bars 355 and 356 rotatably secured at one end to the shaft 344 and extending outwardly from the yoke 342 to provide a framework for supporting additional slip-rings, thermocouples and electrically energized terminals, as shown in FIG. 13. The additional sealing wheels 335 may be positioned at any desired transverse location in the region of the web overlap 334 by suitably manipulating the actuating means

341 for advancing the yoke 342 and associated members attached thereto along the screw 340. Also, each sealing wheel 335 may be mounted at a different transverse location of the overlap 334 to provide a plurality of heat seal lines 20 and 21 in a package formed by the apparatus of this invention, as shown in FIG. 3.

Sealing wheels 335 preferably contact the overlap 334 under pressure which is transmitted thereto by means of a pneumatically operated pressure cylinder 357 which is secured at one end to the cross-bar member 339 and is constructed and arranged to transmit a downward force upon the cross-bar 339 which is transmitted through the yoke 342 to the sealing wheels 335. The sealing wheels 335 contact the area of overlap 334 advancing therewith between an extension 318' of the forming plate 318 (see FIG. 11) and the sealing wheels 335.

Thus, the sealing wheels 335 heat seal the overlapped web layers by means of heat and pressure along a heat seal line, as at 358 as shown in FIG. 10, thereby to form a unitary open-ended tube 50 around the spaced package groups 209 of articles as the package groups 209 are continuously moved through tube sealing means 304, and towards web (now tube) advancing means 305.

The tube advancing means 305, as seen in FIGS. 1, 2 and 10, includes an endless belt 361 adapted to move continuously around suitable sprocket assemblies 362 secured to a supporting frame 303 which, in turn, is secured to frame members 11 of the frame 10. The belt 361 is preferably fashioned of a plurality of transversely disposed members 364 suitably secured to driving chains (not shown) engaging the spaced sprockets 362 one of which may be operatively connected to a drive shaft 365 (FIG. 2).

It is important to note that belt 361 is adapted to contact the top surfaces of the package groups 209 and thus firmly hold or clamp the package groups 209 that are within the tube 50 between it and the conveyor 301 for continuously pulling the web 18 from a film supply source thereof through the tube first and second forming means 302 and 303 and the tube sealing means 304 as the tube 50 is formed from such web 18 and for continuously pulling the tube 50 after it is formed from the tube sealing means 304 and presenting it to the tube weakening section 500, as will be further explained.

FILM SUPPLY AND WEB WEAKENING SECTION

Referring particularly to FIGS. 16, 17 and 18 it will be seen that the web 18 of film formed into the tube 50 comes from a film supply source which includes a movable film roll support 401 consisting of side frame members 402 joined to end frame members 403 resting on wheel supports or casters 404 that are secured to each bottom corner of the support assembly. One of the end frame members 403 is provided with a handle 405 which may be grasped for moving the film roll support 401 by rolling it on the casters 404. Each end frame member 403 has a modified truncated outline having a flat top 406 and tapered sides 407 and also is provided with a slot 408 extending downwardly from about the mid-point of the flat top 406 and a reinforcing member 409 surrounding the slot 408. The slots 408 in each end frame member 403 are adapted to accommodate and support the ends of a support and unwind mandrel 410 having suitable rotatable bearing means 411 mounted thereon for engaging each end of the core portion of large rolls of film thereby to support the film in roll form for unwinding and utilization in the apparatus. Further, each end frame member 403 is provided with a lock means 412 consisting of a rectangular bar 43 pivotably mounted at one end to the end frame, as at 414, and having purchase means 415 extending outwardly from its other end and also has an arcuate slot 416 about mid-length of each rectangular bar 413 adapted to engage a pin 417 extending axially outwardly from the mandrel 410 upon moving the purchase means 415 clockwise, as shown in FIG. 16, thereby to lock the mandrel 410 in position on the film roll support 401.

Movable film roll support 401 is adapted to be positioned in a sub-frame assembly 418 preferably beneath the frame 10. Sub-frame assembly 418 consists of side frame members 419 joined to end frame members 420 secured at 421 to frame members 11 of the frame 10. Sub-frame assembly 5 418 further consists of vertical end frame members 422 at each corner thereof that are joined at the top to the frame members 419 and 420 and rest at the bottom on floor level. Bottom end frames 420' at both ends of the sub-frame assembly and bottom side frames 419' complete the 10 sub-frame assembly 418.

Suitable guide and lock means are provided on the sub-frame assembly 418 for aiding the placement and securing of the film roll support 401 therein. The foregoing is accomplished by means of guide bars 423 suitably secured to the sub-frame assembly 418 having slots 424 extending the entire length thereof adapted to engage and accommodate guide pins 425 that project outwardly from the side frame members 402 of the film roll support 401. As shown in FIGS. 16 and 18, the film roll support 401 is adapted to be wheeled into position by engaging the cooperatively disposed guide pins 425 and the slot 424 and urging the support 401 to travel along the slot 424 until it is seated in place. Thereafter, the film roll support 401 is secured in position by means of lock assembly 426 consisting of rotatable handwheel 427, lock pin 428, and rod or shaft 429. One end 20 of rod 429 is threaded and is adapted to engage a cooperatively threaded nut (not shown) secured to the frame 422, and the other end of the rod 429, which is also threaded, extends through slotted bracket 431 secured to the frame member 422 and engages the handwheel 427 through a centrally cooperatively threaded aperture 432 therein. Lock pin 428 consists of a hollow tube portion 433 and a pin 434 secured thereto to project outwardly from the tube portion 433 and is supported on the rod 429 (which extends through the tube portion 433) adjacent the handwheel 427 and is secured in place thereon by means of nuts 435 and 436. As shown 25 in FIGS. 17 and 18, the pin 434 of the lock pin 428 is adapted to engage a slot 437 cooperatively disposed in a side frame member 402 of the film roll support 401 thereby to secure the film roll support 401 in operative position. Lock assembly 426 can also be utilized for 30 adjusting the lateral location of the roll of film, especially for aligning the centerline of the film with the centerline of tube shaper 314.

It should be noted that it is preferable to apply an 35 unwind brake force for better control of large rotating film rolls, and to this end a tension brake consisting 50 preferably of a wide flat belt 442 drooped over the film roll surface and having a weight 443 secured thereto is provided. Belt 442 is provided with a plurality of apertures 444 at each end thereof adapted to engage pins 445 55 on the sub-frame 418 for securing the belt 442 in position. Alternatively, brake means could be incorporated into bearings 411, but a weighted belt as above described is preferred because such an arrangement provides a relatively uniform tension brake.

From the film supply source, the web 18 of film is 60 first continuously fed or drawn through a web weakening means 450 which is adapted to selectively weaken the web 18 at spaced intervals therealong in a manner and for a purpose further to be described, and from the web weakening means 450 to the tube forming section 300 where the web 18 is continuously formed into the tube 50 and around the spaced package groups 209 of articles as has 65 previously been explained.

As best seen in FIGS. 1, 16, 17 and 28, the web weakening means 450 preferably includes a web weakening blade 451 which is mounted for rotation on the frame member 11 by means of a bracket 452. The blade 451 is removably mounted in a blade holder assembly 453 which consists of a body 454 and a blade clamping bar 455 which is secured to the body 454 by securing 70 75

bolts 456. The blade is slidably received between the body 454 and the clamping bar 455 and the bolts 456 are tightened to secure the blade 451 in place in the bladeholder assembly.

Bladeholder assembly 453 is mounted on a shaft 457 having a drive pulley 458 at one of its ends which is adapted to be driven in a manner further to be described thereby to impart rotatable motion to the bladeholder assembly 453 and, hence, to the web weakening blade 451.

From the film supply source the web 18 is fed over an idler roll 438 secured between the frame members 422 of sub-frame 418, under a backup roll 439 mounted for rotation in brackets 452 secured to the frame members 11 of the frame 10 and into a nip defined by the roll 439 and the bladeholder assembly 453.

The cylindrical surface of the backup roll 439 is of a resilient material, such as rubber, and the web weakening blade 451 is brought to bear firmly against it during each rotation of the bladeholder assembly 453 thereby to form a line or zone of weakness 30 across the width of the web 18 during each rotational cycle. The rotational contact of the blade 451 with backup roll 439 is synchronized so as to form a series of lines of weakness 30 at a predetermined spaced interval along the length of the web 18. The distance between the spaced transversed weakened lines 30, as shown most clearly in FIG. 29, will be such as to enable individual package group 209 of articles to be centered therebetween, still leaving a film surface area between the articles 229 at the ends of each package group 209 and the line of weakness 30 next adjacent the end articles 229.

After the web weakening operation, the web 18 is formed into the tube 50 as has been previously described and the tube 50 with the package groups 209 wrapped therewithin and positioned between the spaced lines of weakness 30 is fed from the tube forming section 300 and into the tube weakening section 500 where the tube 50 is further weakened at or adjacent the lines of weakness 30 in a manner and for purposes further to be described.

TUBE WEAKENING SECTION

As shown in FIGS. 1, 19 and 20, the tube weakening section 500 preferably comprises a tube weakening means 501 including a knife 502, a slideable block 503, bearing blocks 504 and 505, and cam plate 519.

In general, tube weakening means 501 is so constructed and arranged as to weaken the tube 50 of film intermediate each package group 209 and adjacent the lines of weakness 30 formed in the web 18 by moving the knife 502 vertically downwardly a slight distance to nick or cut the tube 50 preferably at the top thereof and preferably adjacent or at the lines of weakness 30 while simultaneously moving with and along the path of travel of the package groups 209 thereby to further weaken or reweaken the tube 50 at or along the lines of weakness 30 thereby to increase the ease by which complete separation of the tube 50 is accomplished in the tube separating and package end shrinking section 600 as will further be described.

Reciprocable knife 502 is operated in timed relation to the endless conveyor 301 by means of the rotatable cam plate 519 which is operatively connected to a suitable drive means. The knife 502 is secured to knife support 506 which is connected to the movable bearing block 504 which has two spaced apertures extending therethrough from top to bottom for slidably engaging vertical rods 507 and 508 that extend completely therethrough. As shown in FIGS. 19 and 20, the rods 507 and 508 are each secured at one end to the slideable block 503 and at the other end to the bearing block 505, and the bearing block 504 is adapted to travel along the rods 507 and 508 in a reciprocating manner in response to the action of cam follower 509 operatively connected thereto as the

latter travels along cam surface or track 510 of the rotatable cam plate 519. Resilient means, such as tension spring 511, having one end secured to the bearing block 504 and the other end secured to the bearing block 505 urges the cam follower 509 firmly against the cam track 510.

The knife 502 also is adapted to reciprocate horizontally in response to the action of cam follower 512 operatively connected to the bearing block 505. Cam follower 512 engages a cam groove 513 in the cam plate 519 and travels therewith upon rotating the cam plate 519. The movement of the bearing block 505 is transmitted to the block 503 by means of the rods 507 and 508. The block 503 is provided with an aperture 514 extending therethrough for engaging and accommodating rod 515 which extends through the aperture and is secured at its ends in standards 517 and 518 that are attached to and supported by the frame member 11 of frame 10. Thus, the block 503 reciprocates between the standards 517 and 518 upon rotating the cam plate 519.

A unique feature of tube weakening section 500 is that cam plate 519 thereof can easily be changed whenever it is desired to utilize the apparatus of the invention for packaging articles of different height.

Another unique feature is that the organization of mechanical elements in association therewith, as depicted in FIG. 19, functions to restrain and firmly hold the tube 50 in position around the package groups 209 through the entire tube weakening operation. For instance, as shown in FIG. 19, wherein article groups 209 travel from left-to-right, the tube 50 is firmly held in position on the left of the tube weakening section 500 between the endless conveyor 301, package groups 209 and the tube advancing means 305, while to the right of tube weakening section 500, the tube 50 is firmly held in position between the endless conveyor 301, package groups 209 and the endless conveyor 601 (which is described hereinafter) whereby to maintain the tube 50 enclosing the package groups 209 taut thereby to better and more easily perform the tube weakening operation prior to presenting the thus weakened tube 50 to the tube separating and package end shrinking section 600 of the apparatus.

TUBE SEPARATING AND PACKAGE END SHRINKING SECTION

As shown most clearly in FIGS. 1a, 21, 22, 23 and 29 the tube separating and package end shrinking section 600 comprises the endless conveyor 301, an endless belt 601, a top plenum chamber 602, a bottom plenum chamber 603, blower or air circulator 604 and suitable ductwork interconnecting the plenum chambers with the air circulator 604 and so constructed and arranged as to provide an enclosure or tunnel 620 through which the tube 50 and package groups 209 travel and where the tube 50 is separated between the package groups 209 into individual tube sections 51.

As shown in FIGS. 1a, 21 and 22, the tube 50 is advanced through the tube separating and package end shrinking section 600 on the endless conveyor 301 described hereinabove. Upon entering the section 600, the top portions of the tube adjacent the top surfaces of each package group 209 contacts the endless belt 601 consisting of endless chains 605 and 606 having pad elements 607 and rods 608 spaced therealong and connected therewith. The belt 601 is supported for vertical adjustment between spaced support members 609 and 610 which, in turn, are connected to the frame members 11 by suitable means, such as posts 611 (FIG. 1) and supported thereby. The endless belt 601 is adapted to be driven in timed relation to the endless conveyor 301 by sprocket assemblies secured between support members 609 and 610 adjacent each end thereof.

It is important to note that the pads 607 and the rods 608 of the belt 601 are similar in construction and design to the pads 308 and the rods 309 of the conveyor 301. Thus, the top portions of the tube 50 ad-

1 adjacent each package group 209 contacts a pad element 607 of the travelling belt 601 upon entering section 600 so it is seen that both the top and bottom portions of the tube 50 adjacent the tops and bottoms of each package group 209 are completely covered and gripped respectively by the pads 607 of the endless belt 601 and the pads 308 of the endless conveyor 301 as the package groups 209 advance through this section 600.

5 The tube weakening and package end shrinking section 600 is adapted to first direct heated air substantially only at the lines of weakness 30 of the tube 50 to shrink the tube 50 in these areas thereby to tear the tube 50 along the lines of weakness 30 to separate the tube 50 into the tube sections 51. This tearing operation or separating operation is made easier because web 18 and the tube 50 have been previously weakened in the web weakening section 400 and the tube weakening section 500.

10 The heated gaseous medium, such as air, is then directed substantially only against the end portions 52 of the tube section 51 which extend past the articles 229 at the ends of the package groups 209 thereby to shrink the ends thereof for engaging the end articles 229 of each package group 209. Preferentially shrinking the end portions of the tube section 51 before shrinking the entire tube section 51 over the package group is preferred because such shrinking secures or locks the end portions 52 in place as shown at 612 (FIG. 21) thereby preventing the tube section 51 from sliding over either the top or bottom portions of the end articles 229 of the package groups 209 when the latter are subjected in their entirety to the package final heat shrinking operation.

15 The heated air is directed against the tube 50 at the lines of weakness 30 to separate it into tube sections 51 and then against the end portions of the tube sections 51 to shrink them into engagement with the articles 229 at the ends of each group 209 by means of the blower 604 which moves the heated air into and through the ductwork 613 to deliver the heated air into the top plenum chamber 602 and the bottom plenum chamber 603.

20 Top plenum chamber 602 is characterized by a flat top wall 614 connected to depending side walls 615 and end walls 616. One of the side walls 615 is provided with an opening 617 for engaging a branch 613' of the ductwork 613 for admitting heated air thereto. The bottom portion of the top plenum chamber 602 is open and provided with a volume flow control means 618 consisting of a plurality of adjustable vanes 619 rotatably secured between the side walls 615 and adapted to be either closed or opened any desirable amount for controlling the amount of heated air circulated therethrough. The bottom portion of the top plenum chamber 602 also is provided with flow direction control means consisting of a plurality of adjustable vanes 621 rotatably secured between the end walls 616. As shown in FIGS. 21 and 22, the entire top plenum chamber 602 assembly is supported between the support members 609 and 610 intermediate upper and lower flights 622 and 623 of the endless belt 601.

25 Heated air passing through the volume flow control means 618 and the flow direction control vanes 621 is directed through the openings between the spaced rods 608 of the endless belt 601, as indicated by arrows A in FIG. 22, onto the tube 50 adjacent the lines of weakness 30 to separate it into the tube sections 51, then onto the end portions 52 of the tube sections 51 extending beyond articles at the ends of each package group and into an enclosure 620. As shown in FIG. 21, the enclosure 620 is defined by the endless conveyor 301, the endless belt 601 and sidewalls 624 and 625 secured between the support members 11, 609, and 610.

30 The bottom plenum chamber 603 is similar in construction and design to the top plenum chamber 602 except that it is secured in position between main frame members 11 intermediate the upper and lower flights of the conveyor 301.

Heated air enters the bottom plenum chamber 603 from

35 a branch duct 613" of ductwork 613 and flows upwardly through the volume flow control means 618 and the flow direction control vanes 621 and through the openings between the spaced rods 309 of the endless conveyor 301, as indicated by arrows B in FIG. 22, onto the tube 50 at the lines of weakness 30 to separate it into tube sections 51 and then onto the exposed end portions 52 of each tube section 51 not covered by the pad elements 308.

40 From this, and referring particularly to FIG. 21, it is seen that during the tube separating and package end shrinking operations, the pads 308 of the conveyor 301 completely mask or heat shield the bottom portions of the tube 50 adjacent the bottom surfaces of each package group 209; that the pads 607 of the endless belt 601 completely mask the top portions of the tube 51 adjacent the top surfaces of each package group 209; and, that the sidewalls 624 and 625 are constructed and arranged to substantially mask the sides of the tube 51 adjacent the sides of each package group 209, as the package groups 209 are continuously fed through the section 600. Thus, substantially only the zones of weakness 30 of the tube 50 before it is separated and the end portions 52 of the tube sections 51 after separation are selectively exposed to the hot air thereby to enable the separating and end shrinking operations to take place. And, very importantly, since the masking pads 308 and 607 are parts of the continuously moving endless conveyor 301 and the endless belt 601, the continuous operation of the apparatus in the tube separating and package end shrinking section 600 is uninterrupted.

45 Heated air in the enclosure 620 is recirculated to the blower 604 via branch duct 613'" that penetrates into the enclosure 620 through the sidewall 625. The recirculating air is heated to any desired temperature by means of an electrical heater device 628 consisting of a plurality of heaters 629 adapted to be connected to a suitable source of electrical energy. The heater device 628 is secured in the return duct 613'" of ductwork 613, as shown in FIG. 23.

50 A unique control feature embodied in section 600 comprises a damper device having a damper plate 626 secured to a rod 627 rotatably mounted in ductwork 613. Rod 627 extends through a wall of the ductwork 613, as indicated at 630, to provide an extension for securing actuating means 632 thereto which consists of a slotted bar 633 having an actuating pin 634 extending through the slot therein. Actuating pin 634 also extends through a spring 635 intermediate the slotted bar 633, and keeper 636 and another spring 637 intermediate the slotted bar 633, and keeper 638, and one end of the actuating pin 634 is connected by suitable means, such as chain 639, to piston rod 640 of pneumatically operated cylinder 641. One end of the spring 635 abuts directly against the slotted bar 633, but the end of the spring 637 adjacent the bar 633 abuts against a keeper 642 secured to the pin 634, and the spring 635 exerts a greater force on the bar 633 than the spring 637 for urging the damper plate 626 clockwise (FIG. 23) so that normally the damper plate 626 restricts air flow through the ductwork 613.

55 Cylinder 641 is adapted to be energized by introducing a hydraulic fluid medium thereto through a suitable valve 643 for moving the piston element therein and piston rod 640 connected thereto for exerting a pull through the chain 639 on actuating pin 634, as shown in FIG. 23, thereby to cause the damper plate 626 to pivot about the rod 627 and rotate counterclockwise, thus permitting the flow of air through the ductwork 613. On the other hand, to prevent excessive build-up of heat in enclosure 645 during temporary operational shutdown of the apparatus, an electrical signal energizes normally open solenoid shut-off valve 644 which also vents the pressure in the cylinder 641 thereby deenergizing the cylinder 641 to release the pull on the pin 634, and thus permit the spring 635 to exert its force against the slotted bar 633 which acts against the keeper 642 to cause the rod 630

and the damper plate 626 to rotate clockwise, as shown in FIG. 23, for restricting the flow of air through the ductwork 613.

Package groups 209 exit from the tube separating and package end shrinking section 600 and advance to the package final shrinking section 700 as separate packages having the film at each end thereof heat shrunken against and about the end articles 229 of each package group 209.

PACKAGE FINAL SHRINKING SECTION

The package final shrinking section 700 comprises a support frame 701, an endless conveyor 702 and suitable ductwork so constructed and arranged to provide a heated enclosure or tunnel 712 through which package groups 209 are moved for final heat shrinking of tube sections 51 thereabout to provide packages as shown in FIG. 3.

Referring particularly to FIGS. 24, 25 and 26, the conveyor 702 includes a plurality of spaced roller elements 704 suitably secured at each end to endless chains 705 and 706. The endless chains 705 and 706 may be driven by any suitable means as by a sprocket assembly operatively secured between support frame members 707 and 708 adjacent each end thereof and coupled to a motor.

The support frame 701 also includes support legs 709 each connected at one end to either of the support frame members 707 and 708 whereby to present the endless conveyor 702 in alignment with the endless conveyor 301 thereby to afford a continuing path or line of movement for the package groups 209.

The ductwork 703 of the package final shrinking section 700 is compartmented to provide in series a heated air supply module 710 and a heated air exhaust module 711, as shown in FIG. 24. The air supply module 710 is depicted in greater detail in FIGS. 25 and 26, and the air exhaust module 711 is shown in greater detail in FIG. 27.

Referring to FIGS. 24, 25 and 26, the heated air supply module 710 comprises a flow duct assembly 713 and a bottom plenum chamber 714 each operatively connected to branch ducts 715 and 716, respectively, of main duct 717 that is operatively connected to air circulator or blower 718. Bottom plenum chamber 714 is similar in construction and design to the bottom plenum chamber 603 of the tube separating and package end shrinking section 600 described hereinabove and is secured in position between the support frame members 707 and 708 intermediate upper and lower flights of the endless conveyor 702.

Heated air is adapted to enter the bottom plenum chamber 714 from the branch duct 716 and flow upwardly through the volume flow control means 719 and the flow direction control means 720 and through the openings between the spaced roller elements 704 and onto the portions of tube sections 51 adjacent the bottom surface of the package groups 209.

Flow duct assembly 713 is of inverted U-shaped cross-section having a main flow passage 721 in communication with side flow passages 722 and 723, and comprises a top wall 724 connected to depending sidewalls 725 and 726 and a bottom wall 727 connected to perforated sidewalls 728 and 729 having a plurality of apertures 730 therein. The perforated sidewalls 728 and 729 are connected to the sidewalls 725 and 726 by means of bottom walls 731 and 732, respectively, thereby to provide side flow passages 722 and 723. Bottom wall 727 of the flow passage 721 is provided with suitable apertures 733 and 734 providing direct communication between the flow passages 721 and 722 and between the flow passages 721 and 723. Bottom wall 727 also is provided with a large aperture 735 having an upstanding flange 736 extending therearound for supporting and accommodating volume flow control means 737 and flow direction control means 738. Volume flow control means 737 and the flow direction control means 738 are identical in construction and design to the volume flow control means 719 and the flow direction control means 720.

Heated air is adapted to enter the flow duct assembly 713 from the branch duct 715 and be distributed therein through the flow passage 721 to the side flow passages 722 and 723 and through apertures 730 in the latter into enclosure 712 and against the portions of the tube sections 51 adjacent the sides of package groups 209.

The heated air in flow passage 721 also is adapted to flow through both the volume flow control means 737 and the flow direction control means 738 and the aperture 735 onto the portions of the tube sections 51 adjacent the top surface of package groups 209.

The heated air entering the enclosure 712 from the flow assembly 713 and the plenum chamber 714 virtually bathes each package group 209 in a sea of hot air which results in the shrinking of the tube section 51 into tight engagement with all of the articles of the group 209 to provide the package 60 shown in FIG. 3.

The heated air exhaust module 711 is shown in greater detail in FIG. 27 and comprises upper plenum chamber 739 and bottom plenum chamber 740 each in communication with return duct 741 which is operatively connected to the blower 718. Upper plenum chamber 739 is provided with flow direction control vanes 741 suitably supported in aperture 742 therein, and the entire plenum chamber assembly is disposed immediately above the package groups 209. The lower plenum chamber 740 is secured between the frame supports 707 and 708 intermediate the upper and lower flights of the endless conveyor 702. The lower plenum chamber 740 also is provided with flow direction control vanes 743 suitably supported in aperture 744 therein. Blower 718 is adapted to exhaust the hot air adjacent the package groups 209 in the enclosure 712 by way of the plenum chambers 739 and 740 and the return duct 741. Also, the exhaust air travelling in the return duct 741 is directed over a bank of electrical heaters (not shown) suitably disposed therein and operatively connected to a source of electrical energy.

The entire package final shrinking section 700 is preferably enclosed by an outer cover or shroud 703 of suitable material such as stainless steel to provide a guard especially against the heated components therein. Suitable insulation also is preferably provided on the inside of cover 703.

APPARATUS DRIVE SECTIONS

The motive power arrangement for driving the apparatus of the present invention is shown in perspective in FIGS. 2 and 2a. The main source of motive power for the apparatus comprises motor 801 operatively connected by means of drive belt 802 to reduction gearbox 803 having output driven power shaft 804 suitably rotatably secured at its outer end to the frame member 11 and adapted to rotate upon energizing motor 801. A sprocket gear 805 is provided on the power shaft 804 which is adapted to engage chain 806 for rotating sprocket gear 807 and shaft 808 to which the gear 807 is secured. Shaft 808 is provided with a 90° gearbox 809 at one end which cooperatively engages 90° gearbox 810 secured to drive shaft 811 for rotating the latter.

Drive shaft 811 is provided with a 90° gearbox 812 which cooperatively engages gearbox 813 secured to the shaft 311 for rotating the shaft 311 and the sprocket gears 310 secured thereto thereby driving the endless conveyor 301.

Drive shaft 811 also is adapted to cooperatively engage gearbox 814 secured to rotatably mounted shaft 815. Shaft 815 is provided with a 90° gearbox 816 adapted to cooperatively engage gear 817 secured to the shaft 605' of the sprocket assembly 605 thereby to rotate the shaft 605' and the sprocket assembly 605 for the driving endless conveyor 601.

Sprocket gear 807 also is adapted to engage drive chain 818 for rotating sprocket gear 819 and the shaft 365 to which the gear 819 is secured. Shaft 365, in turn, is adapted

to rotate the sprocket assembly 362 for driving the endless belt 361 of tube (and web) advancing means 305.

Referring to FIG. 2a, the drive section 900 shown therein derives motive power from rotatable shaft 901 operatively connected to the sprocket assembly 312 of the endless conveyor 301. Shaft 901 is provided with sprocket gear 902 which is adapted to engage chain 903 for sprocket 904 mounted on gearbox 905 suitably secured to the apparatus support frame assembly and having rotatable output shaft 906. The output shaft 906 of the gearbox 905 is operatively connected to phase variator gearbox 907 having rotatable output shaft 908 and hand operable control means 909 for adjusting or varying the timing of the shaft 908 relative to the rotatable shaft 906 and, in turn, to the rotatable shaft 901. Rotatable output shaft 908 of the phase variator gearbox 907 is operatively connected to drive shaft 910 which is operatively connected to gearbox 911 for rotating shaft 912 of the gearbox 911. Rotatable shaft 912 is operatively connected to gearbox 913 having output rotatable shaft 914 operatively connected to shaft 915 which is connected at its other end to the rotatable package grouping screw 201 for driving the latter and grouping the articles 13 on the endless conveyor 101 in the manner described hereinabove. Shaft 112 also is operatively connected to a gearbox (not shown) similar to the gearbox 913 for driving the rotatable article grouping screw 202.

The drive pulley or sprocket 904 is connected by drive belt 959 to the drive pulley 458 which is connected to the shaft 457 on which the bladeholder assembly 453 is mounted thereby to rotate the assembly 453 and the weakening blade 451 mounted therein.

A gearbox 905 also is provided with rotatable output shaft 916 operatively connected to the sprocket assembly 105 for driving the endless conveyor 101.

The electrical conduits and associated electrical control equipment for the apparatus of the invention are preferably mounted in easily accessible housing 23 secured to support frame 10, as shown in FIGS. 1 and 1a. Indicator controls such as temperature control indicators showing the temperature of the heat sealing wheel 335, pressure indicators showing the pressure exerted by the heat sealing wheel 335, indicator lights showing that machine elements are operative and functional, and start and stop switches are suitably mounted on control panel 24, shown in FIG. 1.

OPERATION

In the operation of the apparatus of the present invention the articles 13 to be packaged, such as cans, are fed in adjacent rows 14 and 15 from the article supply section 100 in the direction of arrow A and into the package group forming section 200 wherein the articles 13 are formed into spaced package groups 209 of a given number of articles. The spaced package groups of articles, preferably six in number, are moved along a given line of movement and into the tube forming section 300 where the web 18 of preferably transparent flexible wrapping film is wrapped around the spaced package groups 209 as they move along the line of movement. The web 18 is fed continuously from a source or supply thereof in roll form from the film supply section and web weakening section 400.

The web 18 is weakened at spaced zones therealong and is transformed in tube forming section 300 from a flat sheet into a tubular structure that enwraps the continuously moving spaced package groups 209 with each individual group being positioned between successively formed spaced lines or zones of weakness 30. The opposed longitudinally extending edges of the web 18 are overlapped a suitable amount and heat-sealed together in the region of the overlap to form the unitary open-ended tube 50 around the spaced groups 209 as they move along the line of movement.

The tube 50 is then preferably weakened at or adjacent the spaced lines of weakness 30 in the tube weakening

section 500 as the tube moves and prior to entering the tube separating and packaging and shrinking section 600 where the tube is separated between the package groups 209 and at the lines of weakness 30 thereby to form tube sections 51 each having open end portions 52 which extend beyond the articles 229 at the ends of each package group 209.

After the tube 50 has been separated into tube sections 51, heated air is directed against substantially only the open end portions 52 of each tube section 51 whereby to selectively pre-shrink these end portions 52 into engagement with the articles 229 at the ends of each group 209 of articles. The package groups 209 are next moved through the package final shrinking section 700 wherein each package group 209 in an individual tube section 51 is subjected to a heated medium over substantially its entire surface area thereby to shrink the entire tube section 51 into engagement with all the articles in its package group 209 to provide a unitary package 60 of bundled articles characterized by a wrapping film tightly drawn over the sides, top, bottom and portions of the ends of each article group 209.

The tube separating and package end shrinking operation is best seen in FIG. 29.

As has been described, the tube 50 with its spaced lines of weakness 30, as further weakened in tube weakening section 500, preferably at the top of the tube 50 and adjacent the tube overlap 334, is moved into the tube separating and package end shrinking section 600.

At the time the tube 50 with the spaced package groups 209 wrapped therein enters the tube separating section 600, through the plane as depicted by line V—V, there has been no separating or tearing action along the line of weakness 30 which extends along with sides and along the top and bottom of the tube 50 and between spaced package groups 209 of articles.

Hot air is directed substantially only adjacent the line of weakness 30 along the top of the tube 50 as depicted by arrows A, and along the bottom of the tube 50, as depicted by arrows B, and this hot air shrinks the tube in these areas as it moves through plane W—W.

Further shrinking occurs as movement continues from plane W—W to plane X—X and such shrinking starts tears along the lines of weakness 30 at the top and bottom of the tube 50 which tearing continues until the tube 50 is completely torn along the lines of weakness, at plane Y—Y, thereby to form an individual tube section 51 containing a package group 209 of articles and having end portions 52 extending beyond the articles 229 at each end of the group 209.

The hot air directed between the groups 209, and originally substantially only at the lines of weakness 30 is now directed substantially only at the end portions 52 of the tube section 51 thereby to shrink these end portions 52 against the articles 229 at the ends of each group 209, as depicted at 612, as the tube section 51 moves from plane Y—Y to plane Z—Z.

The preferred package 60 of six articles is shown in FIG. 3 which depicts two contiguous rows 16 and 17 of three containers each bundled in a tube section 51 of tightly fitting heat shrunk film of flexible, transparent thermoplastic material, such as polyethylene. In FIG. 3, the overlapped edge portions of the film are shown at 19 and the heat seal in the region of the overlap is along heat seal lines 20 and 21 that are disposed in a parallel manner with respect to each other. Finger holes 22 may be provided in the region of the film overlap between four contiguous cans or articles for lifting and carrying the package 60.

In another preferred embodiment of the apparatus of this invention, the web weakening means 450 of the film supply and web weakening section 400 may be completely omitted. In this embodiment, the only weakening operation performed is the tube weakening operation at the tube weakening section 500 wherein only the top of

the tube 50 is weakened, and preferably slit, therealong. Surprisingly, the mere slitting of only a portion of the top of the tube 50 is nonetheless sufficient to permit the tube 50 to be completely separated by tearing along a direction line determined by the top slit as the shrinking of the tube 50 occurs in the tube separating and package end shrinking section 600. In effect, the tearing operation starts along this top slit and continues around the tube 50 as shrinking continues.

It is important that the top slit be sufficiently long to assure that the tear will continue around the tube 50 as guided by the slit and that the tube 50 will be separated approximately at the mid-point or line between the package groups 209 of articles. If this does not occur, defective packages, having too little material at the ends for proper end protection, may result. Of course, in this embodiment the time required to complete the tearing of the tube 50 to form the tube section 51 is somewhat greater without the lines of weakness 30 at the sides and bottom of the tube 50 to guide and enhance the tearing or separating operation and also the assurance that the tear will continue to run around the tube 50 in the precise location desired, without wandering for lack of a line to guide or direct it, is lessened.

FIG. 30 shows still another preferred embodiment of the apparatus of this invention in which tube weakening means 460 and 461 are provided to weaken both the top and bottom of the tube 50 prior to the tube separating operation. In this embodiment, the tube weakening means 460 (including knife 462) and 461 (including knife 463) are rotated to selectively weaken the tube 50 at the top and bottom thereof to further enhance the tube separating operation. It is important to note that the tube weakening means 460 and 461 include continuously driven endless rolls; thus, the continuous flow of the machine operation is unhampered by their operation.

When the flat web 18 is formed into the tube 50, the ends of each line of weakness 30 adjacent the edge of the web 18 are preferably positioned one overlapping the other in the area of web or edge overlap 334 of the tube. In the tube forming operation, however, it may be that the ends are slightly spaced from each other and this can effect the smoothness of the tearing or tube separating operation.

Hence, it is often desirable to further weaken the tube 50 at or adjacent the ends of the lines of weakness 30 at the area of tube or edge overlap 334 and this is most effectively accomplished by the tube weakening knife 502 in tube weakening section 500 which weakens the tube in such area, or, if desired, substantially only at the area of the seal.

In this tube weakening operation (i.e., only weakening the tube at the top thereof or only cutting through the edge overlap area 334 of the tube), it is only necessary that the knife 502 be capable of vertical movement to nick or cut the tube 50. Therefore, all mechanical features giving horizontal motion potential to the knife 502, in addition to its vertical motion capabilities, may be eliminated in this embodiment of the invention, at a considerable gain in simplicity of operation.

As previously has been stated, the articles 13 packaged by the apparatus of the invention may be cans or bottles or other appropriate items and any number, such as two or six or eight, may be packaged in a given package group.

In packaging unchimed cans, it is possible to use a film having a thickness of around 1.25 mils but such thickness may tear at the finger holes 22 unless they are located in the package overlap area 19 which, in turn, requires approximately a two inch overlap. This large overlap area increases the possibility that the ends of the lines of perforation 30 may be misaligned.

In this event, it is particularly desirable to weaken the tube 50 at the overlap area 334 by cutting through the

overlap 334 by means of the knife 502 of the tube weakening section 500.

In the packaging of chimed cans, on the other hand, a film thickness of 1.5 mils is preferred because otherwise the chimes would cut through the film. This extra thickness, however, eliminates the need for a large reinforcing overlap area; only a slight overlap is required which lessens the possibility of misaligned lines of weakness at the ends thereof. Hence, in packaging chimed cans, the need for cutting or weakening the tube 50 is decreased.

The weakening of the web 18 in a generally transverse direction to the path of movement the web as shown in FIGS. 2 and 2a can conveniently be accomplished by web slitting or web perforating techniques. The general direction of the web weakened zones 30 should be transverse to the direction of the web movement but it need not be exactly so. Attractive packages can be made by having the web weakened zones 30 in a generally transverse direction but other than at 90° to the longitudinal centerline of the web 18.

The amount of material severed in the slitting or perforating operation to weaken the web transversely can be critical. Enough web material must be left to provide sufficient strength for the tube 50 and the spaced package group 209 to be advanced by the opposing forces impressed on the groups 209 by the conveyor 301 and the belt 601.

The lines of weakness 30 essentially are tear guide lines or means and, preferably are in the form of lines of perforations. If desired, the lines of weakness 30 may be in the form of lines of slits or a score line.

The web 18 is weakened in a manner whereby the web 18 may be fed through the apparatus and wrapped around the articles to form the tube 50 thereabout without premature separation. Further, these lines of weakness must allow the tube 50 to be separated into tube sections 51 in the tube separating section 600 upon initiating a tear force by shrinking the tube 50 at the lines of weakness 30. The lines of weakness 30 then guide the tear around the tube 50 until the tube section 51 is torn or separated from the tube 50.

In weakening the film 18 by perforating or slitting, it has been observed that the speed of separation of the tube 50 depends to an extent on the ratio of cut to uncut area of a particular line of weakness 30. The greater the cut area, the earlier the separation.

Further, the overlapped and sealed area of the tube is more hesitant in separating than the single thickness film areas. This appears to be more pronounced as the overlapped film width which is increased.

It was found that by cutting the overlapped film in addition to perforating it reduced the time required for separation when compared to perforated film only and, though separation occurred earlier, there was no significant change in final package appearance.

It is not a requisite that the lines of weakness 30 be formed at the time that the packages are being made. Pre-slit or pre-perforated film in web form can be purchased and used as the supply of film in performing the method of this invention.

Nor is it necessary in practicing the method of this invention or employing the apparatus of this invention that more than one heat-shrinking operation be used. It is preferred that an initial heat-shrinking be used to shrink and separate the tube between the spaced package groups and to shrink the ends of the tube section against the ends of the package groups and another heat-shrinking operation be used to complete the shrinking of the tube section against all the articles in the group. However, a single heat-shrinking operation is sufficient to shrink the body and the end portions of the individual tube sections 51 into engagement with the articles of each group.

The apparatus of this invention is capable of preparing satisfactory packages from a wide variety of heat shrinkable films. For example, the film may be of any suitable

thermoplastic organic material, such as a polyolefin film or film made from such resins as polyvinylidene chloride, copolymer, polyethylene terephthalate, polystyrene or the like. The film is preferably biaxially oriented.

The film may vary in thickness depending upon the requirements of use.

Heat-shrinking properties may be produced in thermoplastic materials, for example, by heating the solid material to an elevated temperature, stretching the heated material thereby stretching and orienting the molecules in the cooling material while under this stretching tension to a temperature at which the material will retain its stretched or oriented state when tension is released. The subsequent application of heat to the stretched material permits the molecules of the material to return to their original pre-oriented position or state.

A preferred film to be used in the practice of this invention is a biaxially oriented polyethylene, available commercially under the trademark 200 EH-20 "Clystar,"® owned by E. I. du Pont de Nemours and Company. The high tensile strength and high shrink energy make this film particularly suitable for use in the present invention.

I claim:

1. A method of packaging articles in a web of heat shrinkable film wherein the web is wrapped around the articles to form an open-ended tube thereabout and the articles are arranged in spaced package groups in the tube including the steps of:

weakening the web at spaced zones therealong; separating the tube between spaced package groups and along a weakened zone by shrinking the tube at this zone to form a tube section having open end portions extending beyond the ends of a package group of articles; shrinking the open end portions of the tube section into engagement with the articles at the ends of the package group; and shrinking the entire tube section into engagement with all of the articles in the package group to form a package.

2. The method of claim 1 wherein the step of separating the tube by shrinking includes directing a gaseous medium substantially only onto the weakened zone.

3. The method of claim 1 including the step of masking the top, bottom and sides of the tube adjacent the package group as the tube is being separated.

4. The method of claim 1 including the steps of wrapping the web around the spaced package groups and sealing the overlapped edges of the web together to form the tube, and weakening the tube at the overlapped edges thereof.

5. A method of continuously packaging a plurality of articles in a web of heat shrinkable film comprising the steps of:

forming the articles into spaced package groups; moving the spaced package groups continuously along a given line of movement; weakening the web at spaced zones therealong; wrapping the web around the spaced package groups as they are moved along the line of movement; sealing the overlapped edges of the web together to form an open-ended tube around the spaced package groups as they are moved along the line of movement; weakening the tube substantially at each of the weakened zones therealong; separating the tube between the spaced package groups to form tube sections each having open end portions which extend beyond the ends of each package group by selectively shrinking the tube at the weakened zones; shrinking the open end portions of each tube section into engagement with the articles at the ends of each package group of articles; and shrinking each entire tube section into engagement with

all of the articles in each package group to form packages.

6. The method of claim 5 including the step of substantially masking the top, bottom and sides of the tube adjacent each group of articles as the tube is being separated and as the groups of articles are being continuously moved along the line of movement.

7. The method of claim 6 including the step of substantially masking the top, bottom and sides of the tube adjacent each group of articles as the open end portions of each tube section are being shrunk into engagement with the articles at the ends of each group of articles and as the groups of articles are being moved continuously along the line of movement.

8. A method of packaging comprising:
continuously moving articles along a path of movement;
continuously forming the articles into spaced package groups;
continuously wrapping the spaced package groups in a web of heat shrinkable film and overlapping the edges of the web to provide a region of overlap;
heat sealing the web in the region of overlap to form a tube;
heating the tube to shrink the tube and to separate it intermediate the spaced package groups thereby to form tube sections each having open end portions which extend beyond the ends of each package group, the tube being pre-weakened at spaced zones therealong prior to heating the tube to separate it;
heating substantially only the end portions of each tube section thereby to shrink the end portions into engagement with the articles at each end of each package group;
heating each entire tube section thereby to shrink each tube section into engagement with all the articles in each package group.

9. A method of packaging articles in a web of heat shrinkable film wherein the web is wrapped around the articles to form an open-ended tube thereabout and the articles are arranged in spaced package groups in the tube including the steps of:

weakening the tube at spaced zones therealong; separating the tube between spaced package groups and along a weakened zone by shrinking the tube at this zone to form a tube section having open end portions extending beyond the ends of a package group of articles; shrinking the open end portions of the tube section into engagement with the articles at the ends of the package group; and shrinking the entire tube section into engagement with all of the articles in the package group to form a package.

10. A method of packaging articles in a web of heat shrinkable film wherein the web is wrapped around the articles to form an open-ended tube thereabout and the articles are arranged in spaced package groups in the tube including the steps of:

separating the tube between the spaced package groups and along weakened zones by shrinking the tube to form tube sections, and shrinking each entire tube section into engagement with all of the articles in each package group to form packages.

11. An apparatus for packaging articles in a web of heat shrinkable film wherein said web is wrapped around said articles to form an open-ended tube thereabout and said articles are arranged in spaced package groups in said tube, said apparatus including:
means for weakening said web at spaced zones therealong;
means for separating said tube between spaced package groups and along a weakened zone by shrinking said tube at said weakened zone whereby to form a tube

section having open end portions extending beyond the ends of a package group of articles; means for shrinking said open end portions of said tube section into engagement with the articles at the ends of said package group; and means for shrinking the entire said tube section into engagement with all of the articles in said package group whereby to form a package.

12. The apparatus of claim 11 wherein the means for separating said tube by shrinking includes means for directing a gaseous medium substantially only onto said weakened zone.

13. The apparatus of claim 11 including means for masking the top, bottom and sides of said tube adjacent said package group as said tube is being separated.

14. The apparatus of claim 11 including means for wrapping said web around said spaced package groups, means for sealing the overlapped edges of said web together to form said tube, and means for weakening said tube at said overlapped edges thereof.

15. An apparatus for packaging articles in a web of heat shrinkable film wherein said web is wrapped around said articles to form an open-ended tube thereabout and said articles are arranged in spaced package groups and said spaced package groups are arranged between spaced zones of weakness in said tube, said apparatus including: means for separating said tube between said spaced package groups and along said spaced zones of weakness by shrinking said tube whereby to form tube sections each having open end portions extending beyond the ends of a package group, and means for shrinking each said tube section into engagement with all of the articles in each said package group at the top, bottom, sides and ends thereof.

16. The apparatus of claim 15 including means for weakening said web at spaced zones therealong whereby to form said spaced zones of weakness in said tube.

17. The apparatus of claim 15 including means for weakening said tube at spaced zones therealong whereby to form said spaced zones of weakness in said tube.

18. The apparatus of claim 15 including means for weakening said web at spaced zones therealong and means for weakening said tube at spaced zones therealong whereby to form said spaced zones of weakness in said tube.

19. The apparatus of claim 15 including means for directing a heated gaseous medium substantially only against said spaced zones of weakness in said tube.

20. The apparatus of claim 15 including means for masking the top, bottom and sides of a package group during the separating of said tube.

21. The apparatus of claim 15 including means for directing a heated gaseous medium substantially only against the open ends of each said tube section whereby to shrink the open end portions of each said tube section into engagement with the articles at the ends of each said package group and means to mask the top, bottom and sides of each said tube section during said end portions shrinking operation.

22. An apparatus for continuously packaging a plurality of articles in a web of heat shrinkable film wherein said articles are arranged in spaced package groups which are wrapped in said web which is then sealed to form a tube thereabout, the improvement comprising:

means for weakening said tube at spaced zones therealong;

means for separating the tube between said spaced package groups and along said weakened zones to form tube sections each having open end portions which extend beyond the ends of each package group, said separating means including a heat shrinking zone, means for producing a moving stream of heated gas and conducting said stream into said heat shrinking zone, and heat shielding means in said heat shrinking zone and constructed and arranged to direct said stream of heated gas in said heat shrinking

zone substantially only onto said tube at said weakened zones between said spaced package groups; means for shrinking said open end portions of each said tube section into engagement with the articles at the ends of each said package group; means for shrinking each entire said tube section into engagement with all of the articles in each said package group.

23. The apparatus of claim 22 including conveyor means for moving said package groups through said heat shrinking zone, said heat shielding means being operatively connected to said conveyor means and movable in timed relationship therewith in said heat shrinking zone whereby said heated gas is directed substantially only upon said end portions of each said tube section during movement of said package groups through said heat shrinking zone.

24. The apparatus of claim 23 including belt means, said conveyor means and said belt means including masking means for heat shielding the top and bottom of said tube adjacent each said package group during said shrinking of said tube to separate said tube and during said directing of said heated gas against substantially only said open end portions of each of said tube sections.

25. The apparatus of claim 22, said separating means including a chamber positioned adjacent said path of movement of said package groups through said heat shrinking zone, an endless belt having a plurality of spaced pads defining openings therebetween, endless conveyor means for moving said package groups of articles through said heat shrinking zone and having a plurality of pads defining openings therebetween, said endless belt and said conveyor means movable in timed relationship with said package groups whereby said openings in said conveyor means and said belt are aligned with the spacings between said package groups as said package groups pass through said chamber whereby said heated gas in said chamber is directed through said openings in said belt and said conveyor means and substantially only onto said weakened zones in said tube.

26. The apparatus of claim 22 wherein said zones of weakness in said tube comprise tear guide means.

27. A package making apparatus, said apparatus including in combination, a frame, conveyor means mounted on said frame for moving a plurality of articles continuously along a given path of movement, supply means mounted on said frame for supplying a web of heat shrinkable film continuously into operative association with said conveyor means and said articles, article grouping means mounted on said frame for receiving a continuous supply of said articles and forming said articles into spaced package groups, said supply means and said package groups carried by said conveyor means cooperating to form said continuously supplied web into a tube around said package groups as said groups move along said path of movement, a sealing means mounted on said frame adjacent said path of movement positioned and arranged to engage said tube and seal cooperating portions thereof to form a tube around said package groups as they move, and a shrinking means mounted on said frame adjacent said path of movement and positioned and arranged to separate said tube by shrinking said tube between said groups as they move to form tube sections having open end portions and then to shrink the end portions of said tube section and then the entire tube into secure engagement with said all of the articles in said package groups, said shrinking means including a first shrinking unit for separating the tube and for initially shrinking the open end portions of each said tube section into engagement with the articles at the ends of each said package group to retain said articles in said tube section and a second shrinking unit for finally shrinking each tube section into engagement with all of the articles in its package group, said first shrinking unit including

means defining a heat shrinking zone, a means for pro-

3,545,165

25

ducing a moving stream of heated gas and conducting said stream into said zone, and a heat shielding means movable in timed relationship with said package groups and said conveyor means in said zone and constructed and arranged to direct said stream of heated gas in said zone substantially only upon the open end portions of said tube sections.
